UNITED STATES PATENT OFFICE.

GEORGE B. COLLINS, OF PORT ARTHUR, TEXAS, ASSIGNOR TO THE TEXAS COMPANY,
A CORPORATION OF TEXAS.

CLIP-FORMING MACHINE.

Application filed March 31, 1920. Serial No. 370,092.

To all whom it may concern:

Be it known that I, GEORGE B. COLLINS, a citizen of the United States of America, and a resident of Port Arthur, in the county 5 of Jefferson and State of Texas, have invented certain new and useful Improvements in Clip-Forming Machines, of which the following is a specification, reference being had to the accompanying drawings 10 forming a part thereof.

My invention relates to the formation of a clip or the like, which is adapted for attaching or hinging a handle to a sheet metal can or container.

One object of my invention is to provide 15 a simple and effective machine adapted for producing clips of the aforesaid character in large quantities from circular blanks, which constitute scrap material and are 20 produced when the usual filling or pouring hole is provided for in the top of the can.

In the manufacture of cans from tin plate or other sheet metal, a carrying handle is 25 usually required to be hinged or pivotally attached to the top of the can. It frequently has the form of a wire loop which is flattened to provide a straight side which engages the can and another straight side to engage the fingers of the person who is carrying the can by the handle. The wire loop 30 may conveniently be affixed to the can by soldering thereto a clip in which a flute or corrugation is formed to receive the handle loop. It has been my aim to provide an 35 improved machine for quickly and effectively producing clips suitable for this purpose from circular blanks which are cut from the tops of the cans, to insert a screw top for example, and constitute scrap material.

Other objects and advantages of my invention will be set forth hereinafter and I will now describe the same with reference to the drawings and point out the novel features thereof in the appended claim.

Referring to the drawings:

Figure 1 is an end elevation and Figure 2 is a sectional elevation of a clip forming machine arranged and constructed in accordance with my invention.

Figure 3 is a plan view of the machine shown in Figures 1 and 2.

Figure 4 is a partially sectional detail showing the trimmer rolls of the machine

drawn to a larger scale. Figure 5 is a 55 partially sectional detail showing the forming rolls of the machine.

Figure 6 shows one of the circular blanks which are fed to the machine.

Figure 7 shows the blank after it has been 60 operated upon by the trimmer rolls, and;

Figure 8 is a plan view showing the complete clip.

Figure 9 is a sectional view of the clip together with portions of the forming rolls, 65 illustrating their cooperative action in the formation of the clip.

Figure 10 is a sectional elevation in detail showing the chutes for carrying the blanks to the trimmer and forming rollers, re- 70 spectively.

Figure 11 is a plan detail of the chutes showing the arrangement for ejecting the blanks from the cutting rollers.

Figure 12 is a cross section of one of the 75 chutes.

Like parts are designated by the same reference characters in each of the figures.

The handle clip forming machine illustrated comprises a frame 10 which supports 80 a plurality of shafts 11, 12, 13 and 14. As clearly shown in Figure 3 the shaft 11 is provided with tight and loose belt pulleys 15 and 16, the operation of the machine being controlled by shifter 17.

Affixed to the shaft 11 is a forming wheel 18 which cooperates with the forming wheel 19 on the shaft 12, one of the wheels being provided with annular projections producing a central bead 20 and flat shoulders 21 90 adjacent thereto and the other being provided with correspondingly formed depressions or grooves.

The shafts 11 and 12 are supported by bearing blocks 22 and 23 adjustably mounted in the frame 10 of the machine, which is composed of spaced end brackets in the usual manner. The position of the bearing blocks is determined by suitable adjusting screws 24 and 25. The center distance be- 95

tween the shafts 11 and 12 can thus be adjusted to suit the thickness of the sheet metal of which the clips are to be formed.

The shaft 14 is driven from the shaft 11 by means of a sprocket chain 26 which engages the sprocket wheel 27 on the shaft 11 and the sprocket wheel 28 on the shaft 14. The shafts 13 and 14 are interconnected by

spur gears 29 and 30 and cooperating pairs of cutting wheels 31 and 32 are affixed to the shafts 13 and 14.

The blanks of which the clips are formed are fed into a hopper 33 of a chute 36 which delivers the blanks one by one to the cutting wheels where they are trimmed along the lines 34, the form of each clip being changed from that of Figure 6 to that of Figure 7. The chute 36 is provided with ribs 37 to reduce the friction in the sliding movement of the blanks, and with a top or guide member 38 forming a passageway 39 for the passage of the clips, as clearly shown in Figure 12. The top may have an observation slot 40 in order that the operator can see if the blanks are feeding properly.

There would be a tendency for the blanks of Figure 7 to lodge in the depression of the female cutting roller and in order to prevent this an ejector 41 is provided which consists of a finger or extension of the top member 38. The ejector extends between the cutting rollers and after each blank has been trimmed ejects it onto a chute 42 which conducts the blanks one by one to the forming rollers 18 and 19.

The chute 42 is constructed in much the same form as the chute 36; it is provided with a top or guide member 43 and with friction reducing ribs. The passageway for the trimmed blanks may obviously be of a

somewhat smaller width than that of the pathway 39 of the chute 36. The trimmed blanks delivered to the rollers 18 and 19 are operated upon by the forming wheels and are allowed to drop into a bin (not shown), the clips being in the final form as shown in Figure 8.

Attention is particularly directed to the fact that the machine in a simple and direct manner changes a circular disc of sheet metal which is scrap material into a finished clip, having parallel edges and adapted to be soldered on to a can for securing a loop handle thereto.

What I claim is:

A handle clip forming machine comprising a pair of cooperating shearing wheels, a chute for feeding a succession of circular blanks to the shearing wheels, a perforated guide or cover member for the chute having a narrow longitudinal projection extending into the groove of one of the shearing wheels for ejecting the trimmed blanks therefrom, a pair of forming wheels, and a relatively narrow chute adapted to receive the trimmed blanks from the shearing wheels and to carry the blanks to the forming wheels in a fixed position.

In witness whereof, I have hereunto set my hand this 10th day of March, 1920.

GEORGE B. COLLINS.
